Primary Examiner — Susan Bennett Hattan*Assistant Examiner* — Vy Koenig(74) *Attorney, Agent, or Firm* — Themis Law(57) **CLAIM**

The ornamental design for a stool, as shown and described.

DESCRIPTION

FIG. 1 is a front elevational view of a stool showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a perspective view thereof.

The broken lines in the drawing depict environmental subject matter only and form no part of the claimed design.
